UNITED STATES PATENT OFFICE.

RICHARD J. ROULO AND CLAUDE L. ROULO, OF OAKLAND, CALIFORNIA.

SAFETY APPLIANCE FOR ELEVATORS.

1,234,807.

Specification of Letters Patent.

Patented July 31, 1917.

Application filed July 27, 1916. Serial No. 111,597.

To all whom it may concern:

Be it known that we, RICHARD J. ROULO and CLAUDE L. ROULO, citizens of the United States, residing at Oakland, in the county of Alameda and State of California, have invented new and useful Improvements in Safety Appliances for Elevators, of which the following is a specification.

This invention relates to safety appliances for elevators and particularly pertains to means for locking the elevator car control mechanism against movement when the elevator shaft door is in an open position.

It is an object of this invention to provide a safety mechanism adapted to be mounted within an elevator car and to be actuated to prevent the application of power to the car when the elevator shaft door is open.

Another object is to provide a gravity operated controller lever lock which is positive in its operation and which may be instantly released by the movement of the elevator shaft door to allow the car to be moved.

Another object is to provide a locking mechanism which will act positively to lock the controller lever against movement even though the means by which the lock is actuated by the movement of the elevator shaft door have become inoperative.

It is a further object to provide a controller lock for elevators which is simple in its construction and operation and which may be readily applied to the controller mechanism of most elevators now in use.

Other objects will appear hereinafter.

The invention is illustrated in the accompanying drawings in which:

Figure 1 is a view in elevation of a fragmentary portion of an elevator car and the shaft within which it is mounted, the car being shown in section and the elevator controlling mechanism removed to show the connection between the controller handle and the locking mechanism.

Fig. 2 is a view in horizontal section as seen on the line 2—2 of Fig. 1 and viewed in the direction indicated by the arrows, showing the cam bar mounted upon the door and the releasing mechanism with which it engages to actuate the locking device.

Fig. 3 is a view in detail showing the controller and the controller lever and their correlation with the locking mechanism.

Fig. 4 is a view in vertical section as seen on the line 4—4 of Fig. 3 viewed in the di-

rection of the arrows, showing the correlation between the locking members and the controller lever.

Referring to the drawings more particularly, 10 indicates a wall of an elevator shaft which is provided with door-ways, one of which is here shown as closed by a sliding door 11. The door is suspended from a horizontal track 12 by means of hangers 13 and 14 which provide suitable bearings for track rollers 15 and 16. An elevator car 17 is suitably suspended within the shaft and is adapted to be raised and lowered by a power elevating mechanism not shown in the drawings. The elevating mechanism is controlled by a controller 18 mounted within the car and actuated by a controller lever 19 having a suitable hand-grip 20. All of the foregoing parts are of common construction and need not be altered to coöperate with the locking mechanism to which the present invention pertains.

The locking means here provided is adapted to act in a coöperative manner between the slideable door 11 and the controller lever 19. The mechanism here shown consists of a locking sector 21 pivoted upon a pin 22 to the wall 23 of the elevator car. This sector is substantially semi-circular in shape and is formed with a locking notch 24 which is disposed upon the center line of the sector and lies along the arcuate face of the sector. The sector 21 is formed with a radially extending arm 25 which is fitted with a pair of lever engaging pins 26 and 27 which extend perpendicular to the body of the arm and are positioned a sufficient distance from each other to allow the required movement of the lever arm 19 therebetween. It will thus be seen that when the sector 21 is properly mounted within the car, it will engage opposite sides of the lever arm 19 between its pins and will be oscillated as the lever arm is swung from one of its control positions to another. In this manner co-action is produced between the lever and the locking mechanism without interfering with present controller construction.

The arcuate face of the sector 21 is adapted to be borne against by a locking pawl 28 which is formed with a locking end adapted to seat within the slot 24 when the controller lever is in its neutral position, thus rendering the controller inoperative. This pawl is pivoted upon a pivot pin 29 and is formed integral with a counterweight 30 which normally exerts an upward pres-

sure upon the pawl and maintains it in engagement with the arcuate face of the sector. This pawl is adapted to be relieved from the slot 24 by means of the movement 5 of a counterweight lever 31 which is pivotally disposed beneath the pawl and bears against the lower face of the counterweight 30. One end of the counterweight lever is formed with a counterweight 32 which is of 10 greater weight than the counterweight 30 and which will move the pawl from engagement by gravity when the actuating lever 33 is relieved from beneath it by the door actuating mechanism. This lever is formed 15 with an arcuate end portion adapted to bear against a suitable cam face formed upon the lower side of the counterweight 32 and provided to eliminate friction from the movement of the lever 33 thereagainst.

20 The lever 33, which is pivotally mounted within the car, is directly actuated by a connecting rod or cable 34 which engages one end of the lever and extends downwardly through an opening in the floor and there 25 engages one end of a simple lever 35. This lever is pivoted beneath the floor of the car upon a suitable bracket 36 and allows movement to be transmitted from a cable or rod 37 which passes upwardly through the floor 30 of the car and extends out through the ceiling and there engages one arm of a bell-crank 38, the other arm of which is engaged by a rod 39 which lies substantially horizontal and engages the end of a rocker- 35 crank 40 which is pivotally secured within suitable bearings upon the roof of the car and which is directly secured to a spur gear 41 with which it is adapted to rotate and which meshes with a spur gear sector 42.

40 The sector 42 is pivotally mounted to move horizontally upon a pivot shaft 43 and is there secured to an oscillating lever 44 upon the outer ends of which are secured rollers 45 and 46 which are adapted to be encountered by a vertically disposed cam bar 47. This bar is secured to the inner face of the elevator shaft door 11 and it is by its movement that the entire lock operating mechanism above described is actuated.

45 50 The operation of the device is as follows: Under normal conditions and when the elevator door is closed, the cam bar 47 upon the door will bear the relation to the oscillating lever 44 and its rollers as shown in Fig. 55 2 of the drawings. The locking mechanism mounted adjacent the controller may then be operated as desired as the counterweight lever 31 supports the pawl 28 thus preventing the pawl from seating within the slot 24 60 as the sector 21 is moved. The arrangement of the levers and the gear 41 and its sector 42 prevents the device from being overcome by the gravity of the counterweight upon

the lever 31. When the door is opened, the cam bar 47 will encounter the roller 45 65 upon one end of the oscillating lever 44 and will thereby act through the various levers and connecting rods to rotate the actuating lever 33 in the direction of the arrow —a—. This will relieve the pressure of the counterweight arm from the weight 30 upon 70 the pawl and will thus allow it to be controlled by its own weight and fall into the slot 24 with which it must register when the elevator car is stopped.

75 It will be seen that the car cannot be moved until the elevator door has imparted a movement to the oscillating lever 44 and this is done by the cam bar as it moves with the door to the closed position thereof. 80 Upon this travel, it encounters the roller 46 and returns the gears 41 and 42 to their original position. This movement relieves the weighted end of the counterweight lever from the upward pressure of the actuating 85 lever 33 and again allows the pawl to be supported by the weight of the counterweight lever 31 in a position to prevent the pawl from engaging the slot 24 upon the sector 21.

90 95 It will thus be seen that the elevator locking device herein disclosed is simple and positive in its operation and that it will effectively lock the control mechanism of the elevator car against manipulation while the elevator shaft door is open and will only release it upon the return of the door to its closed position.

What we claim is:

1. In a controller lock for elevators, the 100 combination of a pivoted controller lever, a pivoted member having an arcuate edge formed with a locking notch, a pair of spaced pins carried by said pivoted member extending on opposite sides of the lever, 105 a pawl positioned to engage the notch when the lever is in an intermediate position, and means for normally holding said pawl out of engagement with the notch.

2. In a controller lock for elevators, the 110 combination of a pivoted controller lever, a pivoted member having an arcuate edge formed with a locking notch, a pair of spaced pins carried by said pivoted member extending on opposite sides of the lever, 115 a pawl positioned to engage the notch when the lever is in an intermediate position, means for normally holding said pawl out of engagement with the notch, means controlled from a remote point for releasing 120 said pawl, and gravity means for actuating the pawl.

In testimony whereof we have signed our names to this specification.

RICHARD J. ROULO.
CLAUDE L. ROULO.
